ROTARY STEAM ENGINE

Vernon C. Lynch, Western Springs, Ill., assignor
of fifty per cent to Robert Bean, Brookfield,
Ill.

Application May 26, 1939, Serial No. 275,935

9 Claims. (Cl. 121—73)

This invention relates to rotary steam engines and particularly to improvements in the engine construction, in the arrangements for admission and exhaust of steam and the means for controlling the engine operation.

The main objects of this invention are to provide an improved steam engine of the rotary type wherein the inexpensive force of steam is applied tangentially at the periphery of an annular driven member; to provide such a device wherein the reactive force of admitted steam is utilized in addition to the expansive power of the steam; to provide a rotary steam engine having an improved arrangement of steam inlet and exhaust; to provide such a device having improved means for controlling the cut-off of steam admitted to the expansion chamber; to provide a rotary steam engine having improved and simplified valving mechanism and arrangement; to provide a rotary steam engine having an improved arrangement and construction for the cylinder head gates; to provide an improved and simplified arrangement for control and actuation of the cylinder head gates of a rotary steam engine; to provide a rotary steam engine having an improved housing construction; and to provide a simplified rotary steam engine construction wherein the number of moving elements are reduced to a minimum and whereby more efficient operation is obtained.

A specific embodiment of this invention is shown in the accompanying drawings in which:

Figure 1 is a view showing the device in cross-sectional end elevation.

Fig. 2 is a partially sectioned view as taken on substantially line 2—2 of Fig. 1.

Fig. 3 is a view of the gate control cam as taken on line 3—3 of Fig. 1.

Fig. 4 is a view as taken on line 4—4 of Fig. 1, showing the reversing mechanism for controlling the gate actuating cam shown in Fig. 3.

Fig. 5 is a sectional view as taken on line 5—5 of Fig. 2, showing the arrangement of cylinder head gates.

Fig. 6 is a diagrammatic view showing the piping and steam supply control valve arrangement.

Fig. 7 is a sectional view taken on line 7—7 of Fig. 2 and

Fig. 8 is a fragmentary view of the same as taken from the line 8—8 of Fig. 7.

In the form shown in the drawings, my improved rotary steam engine comprises an annular hollow casing formed of two bell-shaped half-sections 1 set face-to-face and bolted together along

their annular peripheries to form a hollow interior within which a disc-like fly wheel or crank element 2 is mounted on a rotatable shaft 3 extending through the casing on the central axis of the same; the shaft 3 being supported on bearings 4 mounted centrally in the walls of the half sections 1 and, as shown, being fixed against axial movement relative to the engine casing by lock nuts 5 threaded onto the shaft 3.

As shown, the central portions of the casing half-sections 1 are substantially bell-shaped so as to provide a somewhat spherical central cavity within the casing and the margins of the bell-shaped portions extend radially outward to terminate in bolting flanges 6 where the two half-sections meet and are joined.

These radially-extending casing portions, between the flanges 6 and the bell-shaped portions, are spaced from each other and shaped to provide a pair of concentric annular channels. The first or innermost channel is a straight walled space communicating with the central cavity and into which the margin of the flywheel or crank element 2 extends. The second channel, which surrounds the first channel, has outwardly curved sidewalls formed to provide a continuously annular peripheral piston chamber 7, having a circular cross section within which are disposed arcuately cylindrical piston members 8 carried on the periphery of the flywheel or crank member 2.

The flywheel 2, which is keyed to the shaft 3 by means of a key 9, is proportioned so that its periphery will be substantially tangential with the inner side of the annular peripheral chamber 7, and the piston members 8, which are designed to fit the annular peripheral chamber 7, are fast on the periphery of the flywheel 2, preferably being formed integral therewith.

As shown, the pistons 8 are two in number 40 and are diametrically disposed on the periphery of the flywheel 2 so that in rotation of the flywheel the pistons travel angularly in the chamber 7. Also, the chamber 7 is divided into three equal arcuate segments by means of shiftable gate 45 members 10 which extend into the annular chamber 7 from each side of the casing and which are arranged to be opened to allow a piston to pass and then be closed to provide a head against which steam admitted into the chamber 7 may expand and exert its force between the piston and the closed gates to cause rotation of the flywheel 2.

A particular feature of my invention is the manner and arrangement by which steam is sup-

plied to the piston chamber 7 and by which the steam is exhausted. As shown, the intermediate portion of each half-section of the engine casing, lying between the central bell-shaped portion and the portion enclosing the annular chamber 7, is formed to provide a continuous annular steam passage, indicated by the numerals 11 and 12 respectively, located so as to be disposed on each side of the flywheel 2 adjacent its periphery. Thus, during rotation of the flywheel 2 in one direction one of these annular steam passages serves as a steam chest and the other passage serves as an exhaust steam receiver. Upon reversal of the engine rotation the function of these passages is reversed and the first becomes an exhaust receiver and the other becomes the steam chest.

As shown, these steam passages 11 and 12 are enclosed except for arcuate ports 13 and 14, respectively, located in the inner side wall of the respective intermediate portions of the casing half-sections and through which the steam passes on its way to and from the peripheral expansion chamber 7 in which the pistons 8 are housed.

Communication between the peripheral expansion chamber 7 and the ports 13 and 14 is provided by passages 15 and 16 which lead from the margins of opposite faces respectively of the fly wheel 2 at the same radial distance from the central axis as the ports 13 and 14, and pass through the body of the fly wheel into the body of the piston 8, where they terminate at respective opposite ends of the piston. Thus, steam from the steam passage 12 will pass through the port 14 and the fly wheel passage 16 and into the expansion chamber 7, being discharged from the center of the rearward or following face of the piston; and steam being exhausted from the expansion chamber 7 will enter the passage 15, opening into the leading face of the piston, passing therethrough to the annular passage 11 from which it is suitably discharged or removed as will be later described.

The ports 13 and 14 extend angularly along the inner side wall of the respective casing intermediate portions and a pair of such ports is provided for each segment of the peripheral chamber 7, defined by the shiftable gates 19, as indicated in Fig. 2 of the drawings; these ports, in the form shown, being approximately 70 to 80 degrees in effective arcuate length and located between the positions of the gates 10. The ports of the respective casing half-sections are, however, not in registry with each other, those of one side or half-section being advanced with respect to those on the opposite side in the direction of fly wheel rotation, so that the ports on the exhaust side will be nearest the gate toward which the piston is moving and the ports on the steam intake side will be nearest the gate against which the incoming steam is being expanded.

This is accomplished by locating the ports for each peripheral segment so that in one casing half section the respective port will begin near the gate at one end of the segment and extend arcuately therefrom toward the other end, while the port in the opposite casing half section will begin adjacent the said other end and extend backward, arcuately, toward the first mentioned segment end.

In this way the ports on either side of the fly wheel 2 will be uniformly spaced with regard to the gates and regardless of the direction

of fly wheel rotation the valving will be the same since the steam side will be the side having the ports first approached by the piston as it passes the gates.

Thus, in the three-segment arrangement shown, each casing half-section will have an inside face view like that shown in Fig. 2 wherein the front or leading end of each port is located approximately 10° inside of the entering gate, assuming the piston to be traveling clockwise as viewed from the inside face side of the half-section casing, or so that the entering end of the steam passage 16 located on the face of the fly wheel 2 will be about one-quarter open as the gate begins to close and in full registry with the port when the piston has moved to the point where the gate is entirely closed.

In the form shown valving of the steam ports 13 and 14 is accomplished by means of a pair of flat annular ring-like valve plates or rings 17 and 18 arranged to lie flatly against the inner faces of the engine casing half-sections, one on each side of the fly wheel 2. These valve rings are formed to fit the inner faces of the half-sections and close the space between the inner walls of the half-sections and the side walls of the fly wheel 2, the fly wheel sliding between the valve rings which are normally stationary, and the inner margins of the valve rings extend into the spherical central cavity of the engine casing where each ring is offset away from the fly wheel as at 19 to provide a pair of shoulders 20 and 21. The shoulder 20 is formed to fit the inside margin of the bell-shaped portion of the engine casing and the shoulder 21 is arranged to fit against a complementary shoulder of the fly wheel 2 so that each valve ring will be securely held in its proper position relative to the concentric ring of ports in the inner walls of the casing sections.

Also, the inner periphery of the offset portion 19 of each ring is provided with gear teeth 22 for coaction with gears 23 and 24, one for each valve ring, which in turn are respectively mounted fast on operating shafts 25 and 26 extending into the casing from each side thereof. Each of these operating shafts extends through the respective casing side wall and is suitably journaled therein as indicated in Fig. 1, the outward end of each shaft being provided with suitable means 27 by which each shaft may be independently rotated.

Each of the valve rings 17 and 18 is provided with steam ports 28 and 29, respectively, of the same size, angular spacing and radial location as the effective area of the ports 13 and 14 in the casing half-sections and since the valve rings are positioned between the casing half-sections and the fly wheel 2, the angular position at which steam cut-off is desired and the location at which exhausting is to begin may be readily adjusted by merely shifting the valve rings angularly by means of the operating gears 23 and 24 and shafts 25 and 26. Thus quick and accurate control will be had. Also, if desired, the means 27 may be arranged to be operated from a governor, not shown, in a manner that will be readily understood by those skilled in this art though such arrangement is not illustrated herein.

The valve rings 17 and 18 are also provided with means to prevent them from springing outward toward the fly wheel 2 when under the influence of steam pressure while serving as cut-off elements on the steam pressure side of the engine. These means are illustrated in Figs. 7

and 8 of the drawings and comprise arcuate shoes 20.1 fixed to the valve ring at one end of each port and arranged to slide in suitable grooves 20.2 formed in the upper and lower surfaces of the steam passages 11 and 12 adjacent to the respective port openings 13 and 14. As shown, the shoes 20.1 are small substantially rectangular plates having upper and lower tongues 20.3 arranged to fit into the grooves 20.2 which plates are fastened to the inner or casting side of the valve plates at the end toward which the piston is moving when the valve plate is serving as a control for incoming steam.

In order to accommodate the shoes 20.1 when the valve plate is in full open position, the steam ports 13 and 14 are made longer than the desired effective length by an amount equivalent to the length of the shoes. Thus the presence of the shoes does not decrease the desired working length or area of the steam port. The shoes 20.1 do, however, provide support for those portions of the valve plates which are under steam pressure when the valve plates are moved or advanced to shorten the point of cut-off or the period of steam admission, thus preventing binding between the valve plate and the fly wheel on the pressure side.

Also as shown suitable annular gaskets or sealing rings 20.4 are provided, between the engine casing and the valve rings, above and below the steam ports to prevent leakage of steam between the valve plates and the inner face surfaces of the casing.

The gates 10, which divide the annular chambers 7 into the segments which serve as the cylinders of this device, are arranged in pairs, there being one pair for each segment dividing line. As shown in Fig. 5, these gates are rectangular plates which extend through the side walls of the casing half-sections, through suitable openings 30 therein, and meet at the center line or axis of the annular chamber 7. As shown, the gate plates 10 are preferably of tapering width, the narrowest part being the meeting edges of the gates and the widest part being the gate portions which project outwardly from the casing side walls. The purpose of this tapering arrangement is to provide a tight fit between the gate and the casing side wall aperture, when the gates are in closed position, and to compensate for wear. Also, as shown the meeting edges of the gates are provided with a tongue and groove arrangement so as to assure tight closure and obviate leakage of steam between the gates during the period of steam expansion. Thus, one gate is provided with a tongue 31 on its inner edge and the other gate is provided with a complementary groove 32 on its inner edge.

As shown in Fig. 1, each of the gates 10 is operated by a bell crank lever 33 which pivots about a pivot pin 34 suitably mounted in a boss on the outside of the respective casing half-section at a suitable point on the bell-shaped portion thereof. One arm 35 of the bell crank 33 extends through a slotted opening in the bell-shaped portion of the casing half-section into the interior thereof where it is engaged by actuating means that will be hereafter described. The other arm of the bell crank extends radially along the outside of the engine casing toward the gate to which it is pivotally fastened by means of a suitable pin 36.

The bell crank arm 33 is normally held in a position close to the outer side wall of the casing half-section, or so that the gates 10 are in

closed position, by means of a looped spring 37 which is supported by the bell crank pivot pin 34 and which has one leg extending over the radially projecting portion of the bell-crank 33, and which has its other leg bearing against the 5 side wall of the engine casing. This spring 37 is of suitable tension so that it will serve as the actuating means to close the respective gate 10 and hold it normally in a closed position.

The means for actuating the bell crank 33 to 10 open the gates comprise a pair of cams mounted fast on the shaft 3 and located one on each side of the flywheel 2. These cams in their rotation with the shaft 3 actuate a plurality of levers 38 which are suitably mounted pivotally on the 15 inside of the bell-shaped portion of the engine casing and arranged to lie in plane parallel with the fly wheel 2. The arms 38 are spaced angularly around the interior of the central cavity of the engine casing and one arm is provided for 20 each bell crank 33. These arms are actuated by the cam arrangement carried on the shaft 3 so as to move in a radial direction relative to the shaft 3 under the influence of the said cam.

Also, as shown in Figs. 1 and 3, the arms 38 are arranged so that the arm 35 of the respective bell crank 33 will rest against the outer end surface of the arm 38, thus as the arm 38 is shifted radially outward by the actuating cam it will in turn actuate the bell-crank 33 so as to 30 cause the respective gate to be withdrawn from the cylinder chamber 7. As shown, the arms 38 are relatively long members and their pivot points 39 are located in bosses formed on the inside of the bell-shaped portion of each casing half section, the locus of the pivots being on a circle of substantially the same diameter of the valve plate gear 22.

The cams which control the operation of the gates 10 are illustrated in Fig. 3 and are particularly designed to permit reversal of the direction of rotation of the engine fly wheel and, as shown, comprise a collar 40 having a pair of oppositely-disposed radially projecting flange-like wing portions 41 located at the inner end of the collar. A ring-like cam plate 42 likewise having opposed radially-projecting flange-like wing portions 43 is then mounted on the collar 40 and a cover plate 44 having flange-like wing portions 45 identical with the wing portions 41 is suitably fastened to the other end of the collar 40. The wing portions 41 and 45 are thus spaced apart and in the space between them the cam ring 42 is held.

As shown, the collar 40 is made fast to the shaft 3 by means of headless set screws 46 and the cam ring 42 is loose on the collar 40, however, movement between the cam ring 42 and the collar 40 is controlled by means of a pair of segment-shaped keys 47 each of which is mounted in a square aperture 48 formed in a respective one of the radially-projecting wing portions 43 of the cam ring 42. Each of the keys 47 is provided with an integral shaft 49 which has one 65 end journaled in the wing portion 41 and which has its other end extending through and projecting beyond the wing portion 45, the location of the shaft 49 being in each case on the radial center line of the respective wing portions. 70

Also as shown in Figs. 1 and 3 each of the keys 47 is provided with a spring 47.1 disposed in an aperture through the key body so as to bear against the two lateral wings 41 and 45, thus providing a friction means to prevent undesired 75

shifting of the key under impact on the camming surfaces of the cam assembly.

The outwardly-projecting portion of each of the key shafts 49 carries a gear 50 fast on its outer end which gear is meshed with a ring gear 51 loose on the shaft 3. The ring gear 51 is held against axial movement relative to the shaft 3 by means of a thrust collar 52 and thus during rotation of the shaft 3 the cam assembly 40, 42 10 and 44 is rotated with the shaft carrying with it the key 47 and its gear 50, together with the ring gear 51 which is loose on the shaft 3.

As shown in Fig. 3, the wing portions 41 and 45 of the cam members 40 and 42 have side surfaces which extend radially from the axis of the shaft 3, and curved end surfaces which are portions of a circular arc having its center at the axis of the shaft 3. Also the projecting wing portions 43 of the cam ring 42 have end surfaces curved along the same circular arc as the end surfaces of the wing portions 41 and 45, but the sides of the portions 43 spread outwardly as they approach the shaft 3 instead of inwardly as the case would be if they were radial with respect to the axis of the shaft 3. The key 47 and the aperture 48 within which it is disposed are so formed that by turning the key by its shaft 49 it will cause the cam ring 42 to shift angularly on the collar 40 and thereby shift the position of the wing portions 43 angularly with respect to the wing portions 41 and 45, thereby throwing the wing portions 43 toward one side or the other of the wing portions 41 and 45. Also, as shown, the outermost corners of the wing portions 41 and 45 are cut off so as to coincide with the respective sides of the wing portion 43 when the cam ring 42 is thrown from side to side under the influence of the key 47.

Thus, the side surfaces 52 of the wings 43 serve as cam surfaces on which the contacting ends 53 of the levers 38 will ride as they follow the surface of the cam ring 42 to reach the curved ends of the wing portions 41 and 45, at which position the levers 38 are swung to their greatest distance radially from the axis of the shaft 3 and at which position the gates 10 are fully open. The length of the arc or cam surface on the ends of the wings 41 and 43 determines the time period during which the gates 10 are held in their fully opened position and is therefore proportioned to permit the piston 3, on the periphery of the fly wheel 2, to fully pass the gate position before the gates are allowed to close, which occurs when the head 53 of the lever 38 reaches the end of the curved surfaces of the wings 41 and 45 and drops off the same onto the body portion of the camming ring 42.

It will now be seen that when the camming ring 42 is shifted angularly to the left of the position shown in Fig. 3, by means of the key 47, that the camming mechanism will then be in position to operate the levers 38 when it is rotating in a counterclockwise direction as viewed in Fig. 3. It will be understood, however, that the angular position of the cam mechanism on the shaft 3 with respect to the position of the pistons 8 will be such that the timing of the operation of the gate actuating means will permit the piston to pass completely through the gates without ever touching the same, the gates beginning to open as the piston approaches, being fully open when the piston reaches the gate position and closing substantially instantly as soon as the piston has fully passed the gate position.

The angular shifting of the position of the cam ring 42 on the collar 40 is effected by rotating the ring gear 51 relative to the shaft 3 and hence relative to the cam assembly, which rotation causes rotation of the gears 50 carried on the key shafts 49, so as to cause angular swinging of the key 47 which in turn, operating in the opening 48 in the cam ring wings 43, causes shifting of the cam ring 42 through coaction of the key 47 and the sides of the key opening 48.

Shifting of the ring gear 51 is effected by means of a rack 54 having a set of teeth 55 arranged to engage and be meshed with the teeth of the ring gear 51, the rack 54 extending transversely through the engine casing to the outside thereof where it may be connected with manual or automatic operating means, not shown. A rack 54 is provided for each cam mechanism assembly and the two racks provided in the device illustrated in Fig. 1 are preferably connected on the outside of the engine for simultaneously operating in a manner not shown.

The number of teeth in the group 55 on the rack 54 is such that upon lateral shifting of the rack in the appropriate direction the ring gear 51 will be turned, relative to the shaft 3, a predetermined distance such as to impart the desired extent of rotation of the key gears 49. Thus, upon shifting of the rack 54 so that the teeth 55 are moved to the position shown in dotted outline at 56, the cam mechanism will be reversed and return of the rack teeth to their first position will reset the cam mechanism to its original condition. It will be understood, of course, that the operation of this reversing mechanism will be done only when the engine fly wheel has completely stopped rotation and appropriate means, not shown, may be provided, if desired, to prevent shifting of the rack 54 while the engine is in operation.

As shown in Figs. 1 and 6, steam supply and exhaust connections 57 and 58 are provided for the annular steam passages 11 and 12 respectively, in the engine casing half-sections. The connections 57 and 58 leading to a four-way valve 59, shown in Fig. 6, which provides communication with a steam supply line 60 and a steam exhaust line 61. Thus, reversing of the steam flow through the engine may be had by merely turning the four-way valve 59 through 90° in either direction and shifting the rack 54 in the appropriate direction. Preferably the rack 54 is suitably linked, in a manner not shown, to the valve 59 so that the two will be shifted simultaneously, thus obviating inadvertent operation of one without operation of the other.

Due to the fact that exhaust steam, having become expanded requires a greater outlet area than inlet area it is necessary to provide auxiliary exhaust ports in each of the casing half-sections 60 in order to make the engine perfectly reversible. Thus, as shown in Figs. 1 and 2, lateral ports 62 are provided at each end of each segment of the annular passage 7.

These exhaust ports are provided in each of the casing half-sections and lead through suitable bosses 63 formed on the outside of the engine casing. Also, each of the ports 62 is provided with a gate 64 which gates may be tied together for simultaneous operation in any desired convenient manner, not shown, the arrangement however being such that all the ports 62 at the end of each cylinder or segment toward which the piston is moving, in passing from end to end of the segment, will be open so long as the 75

piston is moving in that direction; the ports 62 at the other ends of the segments being closed until the engine is reversed when the first mentioned ports will be closed and the others opened. 5 Thus, the steam passages 11 and 12 in the engine half-sections may be of the same size and the steam passages 15 and 16 through the fly wheel 2 and the piston 8 may likewise be of the same size, the increase in exhaust port area being 10 provided by the auxiliary outlets 62. Also, the operating means for the gates 64, though not shown, is preferably linked to the means for operating the rack 54 and the four-way valve 59 for simultaneous operation therewith.

15 As shown in Figs. 1 and 6, the entire engine is enclosed in a closed jacket 65 which provides a surrounding chamber into which exhaust steam passing through the openings 62 and through the openings for the gates 10 may pass, 20 thus serving to keep the entire engine warm for more efficient operation and further to provide lubrication for the moving parts on the outside of the engine casing through the medium of oil entrained in the exhaust steam. This function 25 of the exhaust steam is further enlarged by leading the exhaust connection 61 from the four-way valve 59 directly to the interior of the jacket 65, final exhaust from the jacket being had by way of a connection 66 which may lead to a steam 30 receiver or condenser, or to atmosphere.

In operation, assuming the engine fly wheel to be rotating clockwise as viewed from the right-hand end of the shaft in Fig. 1 and the annular passage 12 to therefore be serving as a steam chest, steam will be emitted into the respective segment-cylinder 1 from the annular passage 12 by way of the steam-passage port 14, the valve disc port 29 and the fly wheel piston passage 16, as the piston completes its movement past each 40 one of the gate positions; such steam passing through the passage 16 to the center of the piston 8 from which it is discharged out the rearward or following face of the piston.

As shown in Fig. 2, wherein the port 14 leading from the annular steam passage 12 and the port 29 in the valving disc 18 are shown in registry with each other, the opening to the passage 16 begins to meet the port 29 just as the piston passes the gates 10, being about one-fourth open 50 as the gates begin to close and being in full registry with the port 29 when the gates 10 reach their fully closed position. From then on steam is discharged through the rearward face of the piston until the cut-off position of the valve disc 55 18 is reached beyond which point the volume of steam supplied to the cylinder expands to further exert its force on the piston 8.

It will now be observed that as the steam is discharged from the piston 8 the reactive force 60 of the steam leaving the piston face will be added to the expansive pressure to drive the piston on its way through the segment-shaped cylinder. Thus, an additional effect of the steam is utilized and the efficiency of the engine is enhanced, the 65 reactance force being of considerable benefit because of its point of application and the leverage obtained with respect to the driven shaft 3.

Exhausting is accomplished through the forward or leading face of the piston and also 70 through the auxiliary ports 62 located at the end of the segment-shaped cylinder toward which the piston is moving. Thus, as the piston travels through the segment-shaped cylinder, expanded steam that might be in the cylinder in front of 75 the piston passes through the passageway 15,

opening into the leading face of the piston and thence through the port 28 in the valve ring 17 and the ports 13 leading to the annular exhaust steam passage 11 which is on the opposite side of the fly wheel from the steam chest passage 5 12. That portion of the exhaust steam passing through the auxiliary outlets 62 is discharged directly into the interior of the jacket 65 surrounding the engine and the exhaust steam from the passage 11 passes therefrom through the 10 steam pipe 57, valve 59 and the pipe 61 into the interior of the jacket 65, all of the exhaust steam being finally removed from the jacket 65 by way of the outlet 66.

As shown, the exhaust passage 15 from the 15 leading face of the piston 8 comes into registry with the exhaust port 28 of the valving disc 17 on the exhaust side of the fly wheel just after the steam inlet passage 16 comes into fully registry with the port 29 of the valving disc 18 so that 20 there will be no back pressure against the forward movement of the piston 8. Also, it will be observed from Fig. 2 that steam enters the segment-shaped cylinder through the passage 16 before the gates 10 are fully closed, thus preventing 25 the piston from momentarily pulling a vacuum on its rearward side.

In the form shown each piston 8 is subjected to three power impulses during each cycle of revolution of the fly wheel 2 and since two oppositely-disposed pistons are provided, there will be a total of six power impulses imparted to the fly wheel during each revolution of the same, each piston going through a cycle of steam admission, expansion and exhaust during its 30 passage through each segment of the annular peripheral passage 1, and the gates 10 being automatically opened and closed to allow the piston to pass and to provide a head against which the steam may be expanded as each piston 8 passes 35 the gate positions. 40

The gates 10 are actuated by means of the two cam assemblies, comprising the parts 40, 42 and 44, through the medium of the arms 38 shown in Fig. 3, and the bell cranks 33 shown in Fig. 1, the bell crank for each respective gate being actuated as the head 53 of the arm 38 rides up on the wing 43 of the cam ring 42 onto the cam surface of the wings 41 and 45 of the cam portions 40 and 44 respectively. 45

As before mentioned, control of the steam valve plates 17 and 18 is had by means of the shafts 25 and 26 and their respective gears 23 and 24 which mesh with the gear teeth on the respective inner peripheries of the valve ring portions 19 and it is by these means, through their control 50 ends 27, that the valve plates 17 and 18 are shifted to vary or adjust the point of steam cut-off and the operating position of the exhaust ports. 55

When it is desired to reverse the rotation of the 60 engine the direction of steam flow through the engine is changed by means of the four-way valve 59, shown in Fig. 6, and the position of the primary camming wings 43 of the cam assemblies is switched from one side of the wings 41 and 45 65 to the opposite side thereof by means of the rack bar 54 which, by rotating the ring gear 51 relative to the shaft 3, causes the gears 60 to turn the key shafts 49 so as to swing the keys 47 in the apertures 48 in the wings 43 and thus move 70 the camming ring 42 relative to the collar portion 40.

Thus when swung to reversed position, the primary camming wings 43 will be in a position to cam the levers 38 outwardly when the cam as- 75

semblies are rotating in the opposite or counter-clockwise direction, when viewed as in Fig. 3. Therefore, since the outer curved surface of the camming wings 41 and 45 are of a length proportioned to permit the piston 8 to pass completely through the gates 10, the gates will be automatically operated in proper relation when the engine is running in a reverse direction.

Thus it will be seen that my improved rotary engine is readily reversible by simply turning the four-way steam valve 59 and by manipulating the rack 54, it being understood, of course, that the gates 64 which control the auxiliary exhaust ports 62 will be arranged to be simultaneously shifted so that the ports at the entering ends of the cylinder-segments will be closed and the ports at the leaving ends of the cylinder-segments will be opened.

The main advantages of my improved engine reside in the simplicity of the construction and in the arrangement whereby the control means for actuating the gates and for controlling steam supply and exhaust are housed within the engine casing, thus minimizing exterior moving parts and facilitating the arrangement of the control means so that a single lever may be used to control both the direction of steam flow through the engine and the shifting of the gate control cams for the reversing operation. Another advantage of my improved rotary steam engine resides in the construction and arrangement of the gate-operating cams whereby a single cam assembly mounted on the main driven shaft may be utilized for both forward and reverse rotation of the driven shaft, thus simplifying the engine construction and minimizing the number of camming elements required to effect a completely reversible operation.

Another advantage of my invention is found in the arrangement of steam supply and exhaust passages so that the two may be readily interchangeable and further in the arrangement whereby steam supplied into the segment-shaped cylinders for the power impulse is led to and discharged from the face of the piston, thereby utilizing both the expansive and reactance forces in the steam. Another advantage is found in the construction and arrangement of the steam valving discs located on the inside of the engine and coacting directly with the driven fly wheel 2 whereby the number of valving parts are minimized and whereby either manual or automatic control is facilitated.

A further advantage resides in the shape and construction of the gates which provide the cylinder heads of the segment-shaped cylinders into which the peripheral channel 7 of my engine is divided, which construction automatically provides compensation for wear on both the abutting ends of the gates and on the sides of the same.

A still further advantage of my improved engine resides in the shape and construction of the engine casing wherein the central portions of the two half-sections making up the casing are bell-shaped so as to minimize expansion in the radial direction and thereby obviate binding on the pistons. Further advantages of my improved engine reside in the arrangement whereby the entire engine is surrounded by a jacket into which the exhaust steam is discharged, the provision of such a surrounding jacket serving not only to keep the engine and its operating parts warm for more efficient operation, but also providing a means for carrying lubrication to the various moving parts, such lubrication being supplied by

oil entrained in or carried by the exhaust steam. The presence of the surrounding jacket also provides a means for recovering lubrication oil which will tend to settle to the bottom of the jacket where it can be readily removed.

Although but one specific embodiment of this invention is herein shown and described, it will be understood that details of the construction shown may be altered or omitted without departing from the spirit of this invention as defined by the following claims.

I claim:

1. A rotary steam engine comprising a rotatable shaft, a crank wheel fast on said shaft, a plurality of piston members fast on the periphery of said crank wheel, a casing surrounding said crank wheel and pistons and having opposed axial openings through which said shaft extends, said casing having an annular channel peripherally surrounding said crank wheel and within which said pistons fit and travel, angularly spaced retractable gates arranged to divide said channel into closed angular segments, each of said pistons having a pair of steam passages therein respectively opening from opposite end faces of the piston and each leading therethrough and through said crank wheel to an opening in the margin of a respective side of said crank wheel, and said casing having an annular steam channel on each side of said crank wheel adjacent the margin thereof, said steam channels each having angularly extending and spaced port openings positioned to register with the path of said crank wheel passages, adjustable valve means arranged to vary gradually the angular location of the cut-off of said ports, and means to retract and then close said gates to permit said pistons to pass the same as each of said pistons reaches a gate position during rotation of said crank wheel.

2. A rotary steam engine comprising a rotatable shaft, a crank wheel fast on said shaft, a plurality of piston members fast on the periphery of said crank wheel, a casing surrounding said crank wheel and pistons and having opposed axial openings through which said shaft extends, said casing having an annular channel peripherally surrounding said crank wheel and within which said pistons fit and travel, angularly spaced retractable gates arranged to divide said channel into closed angular segments, each of said pistons having a pair of steam passages therein respectively opening from opposite end faces of the piston and each leading therethrough and through said crank wheel to an opening in the margin of a respective side of said crank wheel, and said casing having an annular steam channel on each side of said crank wheel adjacent the margin thereof, said steam channels each having angularly extending and spaced port openings positioned to register with the path of said crank wheel passages, a valving ring disposed on each side of said crank wheel between said ports and said crank wheel, said valving rings each having ports therethrough of substantially the same size as and registering with said steam channel ports, means to adjust said valving rings angularly relative to said casing and said steam channel ports to vary the angular position of the cut-off of said steam channel ports, and means to retract and then close said gates to permit said pistons to pass the same as each of said pistons reaches a gate position during rotation of said crank wheel.

3. In a rotary steam engine a crank wheel

having a continuous annular rim portion, and a plurality of angularly spaced piston members fast on the periphery of said rim portion, each of said piston members having a steam passage therein opening from an end face of the piston and leading therethrough and through the rim portion of said crank wheel to an opening in the margin of a side wall of said rim portion, a casing surrounding said crank wheel and having a continuous annular channel around the periphery thereof within which said pistons fit and travel, said casing having an annular steam channel in its side wall adjacent the margin of said crank wheel and a plurality of angularly spaced annularly extending ports leading therefrom to the steam passage in said crank wheel, a valving ring disposed between said steam channel ports and said crank wheel and having angularly spaced ports therethrough of substantially the same size as and registering with said steam channel ports, and means to adjust said valving ring angularly relative to said casing to vary the angular position of the cut-off of said steam channel ports.

4. In a rotary steam engine a crank wheel having a continuous annular rim portion, and a plurality of angularly spaced piston members fast on the periphery of said rim portion, each of said piston members having a steam passage therein opening from an end face of the piston and leading therethrough and through the rim portion of said crank wheel to an opening in the margin of a side wall of said rim portion, a casing surrounding said crank wheel and having a continuous annular channel around the periphery thereof within which said pistons fit and travel, said casing having an annular steam channel in its side wall adjacent the margin of said crank wheel and a plurality of angularly spaced annularly extending ports leading therefrom to the steam passage in said crank wheel, a valving ring disposed between said steam channel ports and said crank wheel and having angularly spaced ports therethrough, a shoe on the outer face of said valving ring at the end of each of the ports therein and arranged to fit into the respective steam channel port, said steam channel ports each having a groove in each of its angularly extending oppositely facing margins arranged to slidably and interlockingly receive a respective shoe, and means to adjust said valving ring angularly relative to said casing to vary the angular position of the cut-off of said steam channel ports.

5. A rotary steam engine comprising a rotatable shaft, a crank wheel fast on said shaft, a plurality of angularly spaced pistons on the periphery of said crank wheel, a casing surrounding said crank wheel and having a continuous annular channel surrounding the periphery of said crank wheel, said pistons being arranged to fit into and travel along said channel during rotation of said crank wheel and said casing having central lateral openings through which said shaft extends, angularly spaced retractile gates extending into said channel through the side walls of said casing and dividing said channel angularly into closed segments, and means to open and close said gates as each of said pistons passes a gate position, said gates each comprising a pair of flat-sided plates opposed and abutting end to end within said channel and having their sides converging toward the abutting ends, one of each pair of said plates having a tongue extending along its abutting

end and the other having a complementary groove on its abutting end to receive said tongue.

6. In a rotary steam engine of the class described having a rotatable driven shaft, a gate operating cam comprising a collar fixed to said shaft and having angularly spaced radial wings projecting from each end, the wings of one end being in angular registry with the wings of the opposite end, and all said wings having arcuate ends and side edges radial with respect to the driven shaft axis, a cam ring journaled on said collar between the end wings thereof and having radial wings with the same angular spacing as said collar wings, said cam ring wings having arcuate ends of less arcuate length than said collar wings and side edges diverging therefrom toward said collar, and means to shift said cam ring angularly with respect to said collar to shift the cam ring wings from one side to the other of the said collar wings.

7. In a rotary steam engine of the class described having a rotatable driven shaft, a gate operating cam comprising a collar fixed to said shaft and having angularly spaced radial wings projecting from each end, the wings of one end being in angular registry with the wings of the opposite end, and all said wings having arcuate ends and side edges radial with respect to the driven shaft axis, a cam ring journaled on said collar between the end wings thereof and having radial wings with the same angular spacing as said collar wings, said cam ring wings having arcuate ends of less arcuate length than said collar wings and side edges diverging therefrom toward said collar, and each of said cam ring wings having a rectangular opening therein, a key fitted into each of said wing openings and having an operating shaft extending through and journaled in an aperture in a respective collar wing at one end of said collar, a ring gear free on said driven shaft at said one end of said collar, a gear on the outer end of each key shaft and meshed with said ring gear, and means to rotate said ring gear relative to said driven shaft whereby said keys will rotate to shift said cam ring.

8. A rotary cam comprising a driven shaft, a collar fast on said shaft, a ring loose on said collar, and an end plate secured against one end of said collar, said collar having a radially projecting wing at its other end and said ring and plate each having a radially projecting wing, all said wings being in arcuate registry and of the same radial length and having arcuately curved end surfaces, said collar and end plate wings having side edges extending radially with respect to the axis of said driven shaft, and said ring wing having an end surface of less length than the other wings and side edges diverging from its end toward said driven shaft, and means to shift said ring angularly relative to said collar to throw the ring wing from one side edge to the other of collar and end plate wings.

9. A reversible rotary cam comprising a driven shaft, a collar fast on said shaft, a ring loose on said collar, and an end plate secured against one end of said collar, said collar having a radially projecting wing at its other end and said ring and plate each having a radially projecting wing, all said wings being in arcuate registry and of the same radial length and having arcuately curved end surfaces, said collar and the end plate wings having side edges extending radially with respect to the axis of said driven shaft, and said ring wing having an end surface

of less length than the other wings and side edges diverging from its end toward said driven shaft, said ring wing having a rectangular opening therein, a key fitted into said opening and having an operating shaft extending through and journaled in an aperture in one of the other wings, said key and ring wing aperture being arranged to cause lateral shifting of said ring wing relative to said key operating shaft upon

rotation thereof, a ring gear loose on said driven shaft, a gear on said operating shaft meshed with said ring gear, and means to rotate said ring gear relative to said driven shaft whereby said operating shaft will turn said key and shift said ring wing from one side to the other of the collar and plate wings. 5

VERNON C. LYNCH.
